UNITED STATES PATENT OFFICE.

KATE CONDON, OF CHICAGO, ILLINOIS.

STOCKING PROTECTOR.

Application filed June 25, 1928. Serial No. 288,113.

My invention relates to stocking protectors and it has among its objects the provision of improved protecting device adapted to be slipped over the heel and toe portions of the 5 foot to prevent damage to stockings.

The novel features of the invention will be best understood from the accompanying description of an exemplification of the invention, reference being made to the accompanying drawings, wherein

Fig. 1 is a perspective view of the stocking protector of my invention as worn on the leg;

Fig. 2 is an elevational view of the stocking protector; and

Fig. 3 is a plan view of the stocking protector.

The heel and toe portions have always been the most vulnerable parts of stockings and subject to greater wear and injury than any 20 other parts of this article of wear. The problem of protecting these portions of the stockings became of even greater importance in view of the wider use of sheer, thin hose that became established within recent years, particularly in view of the much greater cost of 25 such stockings as compared with those worn in years past.

In order to reduce the damage to stockings at the heel and toe portions, various types of 30 protectors have been proposed in the past but none have found a wide use because, as made heretofore, they either detract from the appearance of the stocking as worn in modern low cut shoes or fail to fit properly 35 and sit in place on the foot.

My invention provides an improved stocking protector which has a firm, close fit on the foot, sits thereon firmly and permits slipping on the stocking over the foot without becoming curled and displaced, and yet covers 40 only the relatively small portions of the foot at which the stockings are subject to damage at the toe and heel portions thereof.

As shown in the drawings, my improved 45 protector comprises a knitted fabric forming a heel portion or socket 1 adapted to fit the heel portion of the foot, a toe portion or socket 2 adapted to fit over the toe portion of the foot, and a narrow intermediate portion 3 connecting the heel and toe portions. As seen

in the drawing, the intermediate portion 3 is of much narrower width than the portion of the foot which it underlies, this being particularly indicated in Fig. 1 and in Fig. 3, the latter figure having the width of the foot 55 indicated by dotted lines 4. The heel and the foot portions 1 and 2 have the edges or contour so shaped that when the protector is on the foot, and the cut-out slipper as now worn placed thereover, the foot protector will 60 be entirely covered by the shoe and no single portion thereof will be seen from the outside.

In a protector of the type shown in the drawing, it is of extreme importance to have the toe and heel portions fit snugly on the 65 foot while the stocking is slipped thereover because much annoyance is experienced if the portions of the protector slip from place or curl and require adjustment in pulling in place after the stocking has been placed 70 on the leg. Very often it is almost impossible to make the adjustment and the curled or misplaced portion of the protector will exert pressure on the foot and cause hurt and abrasion thereto. The shaping of the protector, 75 as shown in the drawing, avoids the above mentioned difficulties because the narrow intermediate portion of the protector exercises a pulling action on the edges 5 and 6 of the toe portion and the edges 7 and 8 of the heel 80 portion so as to fit snugly and in place on the foot and stay there without slipping while the stocking is pulled thereover. In order to secure such a snug fit the fabric constituting the protector is so knitted that the edge 85 portion of the protector along the lines 5, 6, 7 and 8 is somewhat shorter than the adjacent portions back of the edge so that the edge portion fits somewhat tighter on the foot than the other portions of the protector. This prevents curling of the edges and secures a tight and correct fit of the protector although the area covered by the protector is limited to 90 only small portions of the foot. In the preferred construction, the edge portions 5 and 6, 7 and 8 of the protector are of somewhat reinforced fabric, for instance, by putting an additional splicing thread along the selvage edge of the protector in order to secure the tensioning of this portion of the protector 95 100

when placed on the foot as explained above. In other words, I make the protector so that when placed on the foot the main portion of the protector over the toes 2 and the heels 1 5 will stretch more readily than the portion at the edges 5, 6, 7 and 8, the portions of greater tension being indicated by the multiple lines along said edges.

The additional tensioning of the edges of 10 the protector may also be obtained by knitting the loops forming the edges somewhat closer than the remainder of the fabric so that when placed on the foot the edge portion offers more resistance against stretching than 15 the other portions of the fabric, thereby holding the protector in place.

By the use of the foregoing protector, runs 20 of the threads in the silk stockings as now in vogue are prevented since the protector is worn against the skin eliminating contact of 25 the nails of the toes with the stockings and likewise preventing injury to the heel portion. At the same time the protector does not disturb the appearance of the stocking 30 because the portion of the foot around the instep, which is exposed at the openings of the modern pumps or slippers, is not covered by the protector so that it is not visible through the thin portions of the stocking covering 35 these parts of the foot. By the use of a narrow intermediate portion the upper edges of the toe portion and of the heel portion are elastically pulled towards the narrow sole portion and held tightly against the foot preventing 40 curling or displacing of the protector and wrinkling of the fabric. A nice fit is thus secured without impairing the appearance of 45 the stockings as worn in modern shoes.

The invention is not limited to the precise 50 details as shown and described above but I desire that the appended claims be given a broad construction commensurate with the art of the scope of the invention.

I claim:

45 1. In a fabric stocking protector comprising a toe portion adapted to underlie and engage over the toes when worn, a heel portion adapted to underlie the heel and engage the rear and sides thereof, and a narrow sole strip 50 connecting the toe and heel portion, said sole strip being of less width than the part of the foot which it underlies, the edges of the toe and heel portions being shorter than the immediately adjacent portions of the fabric so 55 that the edges of the protector firmly grip the foot when worn to avoid curling or displacement.

2. A stocking protector of knitted fabric, a toe engaging portion having its edges shortened and reinforced, a heel engaging portion having its edges shortened and reinforced, a narrow sole strip adapted to underlie the instep connecting said toe and heel portions, said sole strip being of less width than the 60 part of the foot which it underlies, the edges 65

of the toe and heel portions of the protector being drawn into snug engagement with the foot by normal tension of the sole strip when the protector is worn.

In testimony whereof I have hereunto subscribed my name.

KATE CONDON.
